J. H. BOYE

CURTAIN ROD

Filed Oct. 27. 1922

Inventor:

James H. Boye,

By Samuel N. Fonda,
Atty.

Witness:

A. J. Sauer.

UNITED STATES PATENT OFFICE.

JAMES H. BOYE, OF CHICAGO, ILLINOIS.

CURTAIN ROD.

Application filed October 27, 1922. Serial No. 597,274.

To all whom it may concern:

Be it known that I, JAMES H. BOYE, a citizen of the United States, residing at Chicago, in the county of Cook and State of Illinois, have invented certain new and useful Improvements in Curtain Rods, of which the following is a specification.

This invention relates to improvements in curtain rods, and has reference more particularly to sectional rods of the flat type which are commonly made of thin sheet metal with the upper and lower margins folded rearwardly and inwardly, forming a substantially hollow structure of oval or 15 oblong cross-section. Many rods of this type are made extensible to fit varying widths of window and door frames, and to this end comprise end elements that are mounted in supporting brackets on the window or door 20 frame, and an intermediate element telescopically engaged with the end elements. Where curtain rods of unusual length are desired or required, the intermediate element itself is frequently made in two or more sections 25 telescopically engaged with each other, this being done partly for convenience in packing and shipment to reduce the length of the package, and partly to afford greater flexibility in respect of longitudinal adjustment by using or omitting altogether one or 30 more of the sections of the intermediate element.

One serious fault in curtain rods of this type lies in the fact that, when made of considerable length and employing several telescoping elements to obtain the required length, they are unduly weak, and under the weight of the curtains tend not only to sag in a vertical plane, but also to warp or twist. 35 That is, the upper edge of the intermediate element of the rod bends laterally and downwardly and its lower edge correspondingly bends laterally and upwardly, causing the central portion of the rod to more or less closely approach a horizontal plane and presenting an unsightly appearance.

The main object and purpose of the present invention is to provide an improved construction which, in a long sectional rod 40 will greatly reduce and substantially eliminate the above-noted fault; and this object

is attained through the provision of an improved means for separably uniting the sections of the intermediate element of the rod whereby much greater strength and rigidity 55 to resist sagging and warping under the load of the curtain is obtained.

Another annoying fault which the ordinary extensible rod composed of telescoping sections presents lies in the fact that, in sliding the curtains lengthwise of the rod, the fabric of the pocket of the curtain, or the curtain rings or hooks (where the latter are employed) tend to catch and stick on the exposed ends of the outer telescoping sections, thus making it somewhat difficult to 60 adjust the curtains to desired position.

Another object of my present invention is to provide a sectional rod, the upper margin of which will for the most part be smooth 65 and substantially continuous, so that the upper edge of the curtain or the curtain rings or hooks may be readily drawn thereover by simply pushing the curtains to one side or the other. A further object of the 70 invention is to provide a sectional rod of such a character that it may be packed and shipped in small compass, and will by its construction readily disclose its proper manner of assembling and mounting to users unfamiliar with its structural features. 75

A still further specific object of the invention is to provide a novel and improved device for strongly and rigidly, and also separably, joining the meeting ends of two 80 hollow curtain rod sections, so as to secure the advantages above mentioned, irrespective of the particular cross-sectional form of the rod.

In order that my invention may be readily 85 understood by persons familiar with the art, both as to its structural features and manner of use, and as to its inherent advantages, I have, in the accompanying drawing, illustrated one practical embodiment thereof 90 which in practice has been found to satisfactorily effectuate the stated purposes and objects of the invention; and referring thereto—

Fig. 1 is a perspective elevation of my improved curtain rod, showing the intermediate element thereof as composed of two separable 100

sections joined by my improved connector;

Fig. 2 is a similar view showing a somewhat longer rod, the intermediate element of which is composed of three sections united by my improved connector:

Fig. 3 is an enlarged cross-section taken on the line 3—3 of Fig. 2;

Fig. 4 is an enlarged longitudinal section taken on the line 4—4 of Fig. 2;

Fig. 5 is an enlarged fragmentary elevation showing one end of an intermediate section with the connector or splice inserted therein; and

Fig. 6 is a perspective elevation of the connector or splice.

Referring to the drawing, 10 designates each of the end elements of a tubular flat curtain rod, herein shown as of elbow shape, with their rearwardly projecting ends 20 adapted to engage with suitable brackets (not shown) attached to the wall. The straight intermediate element of the rod, as shown in Fig. 1, comprises a pair of straight flat tubular sections 11 which at their outer 25 ends telescope over the inwardly extending arms of the end elements 10 with a snug sliding fit, whereby the adjustability of the rod in point of length is obtained. The inner ends of the curved end elements 10 are 30 preferably equipped with friction springs 12 in rubbing contact with the upper and lower edges of the outer telescoping section 11 to secure increased rigidity, as disclosed and claimed in my former Patent No. 35 1,309,060 dated July 8, 1919; but this feature in itself forms no essential part of my present invention.

The intermediate sections 11 are of uniform and equal width and thickness, and 40 the meeting ends of these sections are each formed on the front face with a semi-circular notch 13 in the end edge of the face and with a hole 14 a slight distance in rear of the notch 13.

45 15 designates as an entirety the connector or splicing member. This consists of a short section, preferably six to eight inches in length, of metal stock of a size and shape to tightly interfit with the meeting ends of the rod sections 11. This splicing member is preferably made of sheet metal of much greater strength and rigidity than the stock of the rod itself, and bent into the form of the latter, as clearly shown in Fig. 3, wherein the relative thicknesses of the rod stock and the connector stock are shown. From the rear side of the front face of the connector there are punched outwardly a central protuberance or boss 16, and a slight distance on either side of the latter two additional protuberances or bosses 17. The connector 15 is first driven into the end of one of the sections 11, and in so doing the boss 17 on the entering end, passing beneath the 60 edge of the notch 13, springs the metal form-

ing the face of the rod section outwardly until it comes into register with the hole 14, whereupon it snaps into yieldable locking engagement with said hole. The meeting end of the other rod section 11 is then forced over the exposed half of the connector 15, its end notch 13 riding over the lug 17, in the manner already described, until its end meets and squarely abuts against the end of the other section 11. 70 This brings the end notch into register with the other half of the central boss 13 and simultaneously brings its hole 14 into yieldable locking engagement with the other boss 17. When the rod sections are thus united, the connector or splice 15 is wholly concealed except as to its bosses 16 and 17, and the intermediate element of the rod presents a straight, smooth and practically continuous appearance. However, the sections 11 may be separated by a pull sufficient 80 to overcome the yieldable locking hold of the lugs 17. Preferably one of the lugs 17 is made slightly higher than the other, so that in separating the rod sections the same lug (the lower) will always yield, leaving the splicing element within the end of the other section.

The relatively heavy and inflexible splicing elements 15, tightly fitting the meeting end portions of the intermediate rod sections 11, greatly stiffen the latter at these points against both downward bending or sagging in a vertical plane and lateral twisting or warping; thereby making it 100 practicable to employ a longer rod, without any intermediate supporting bracket or brackets than has heretofore been possible. It will also be noted that the specific structure of the connector or splice, with its central boss 16 engaged with semi-circular notches in the meeting ends of the rod sections insures that the connector or splice will always be centrally located with reference to the meeting ends of the rod sections, extending an equal distance into each of the latter, thereby affording equal strengthening and stiffening effects to the rod sections. The notching of the end edges of the rod sections to encircle the central boss 16 obviously permits the squared ends to meet in a perfect registration, thus creating a smooth and substantially continuous upper edge throughout the entire intermediate portion of the rod lying between the exposed portions of the end elements 10, so that the curtains may be drawn apart or together without any catching of their upper ends on the upper edge of the rod.

In practice the intermediate sections are 125 preferably made equal in length and substantially equal to the length of the end sections; so that, when the rod is fully disassembled, the several sections can be packed side by side in a box or other package but 130

slightly exceeding the length of a single section; and the manner in which the sections are to be assembled for mounting is obvious from mere inspection.

5 Finally, it is manifest that the described advantages of the snugly fitting internal connector or splice which joins the sections of the intermediate element are not dependent upon the particular cross-section or 10 form of the rod herein shown; but are also present when the connector is used in rods of round or other cross-sectional form, provided it is so made as to snugly fit the meeting ends of the rod sections, and is of 15 heavier and stronger stock than the rod itself.

I claim:—

1. An extensible hollow curtain rod of the flat type, comprising end elements, and an 20 intermediate element telescopically engaged with said end elements, said intermediate element comprising a plurality of endwise abutting sections of equal cross-sectional dimensions and an internal hollow splicing 25 member of greater strength and rigidity than said sections snugly fitting the meeting ends of the latter.

2. An extensible hollow curtain rod of the flat type, comprising end elements, and 30 an intermediate element telescopically engaged with said end elements, said intermediate element comprising a plurality of endwise abutting sections of equal cross-sectional dimensions and an internal sheet 35 metal splicing member of the same cross-sectional form as, and of greater thickness

and rigidity than, said sections snugly fitting the meeting ends of the latter.

3. In a curtain rod, the combination with 40 a pair of hollow endwise abutting rod sections, of means for separably uniting said sections end to end comprising an internal splicing member snugly fitting the meeting ends of said sections, said rod sections and splicing member having co-operating devices for locating the joint between said rod sections at the longitudinal center of said splicing member. 45

4. In a curtain rod, the combination with 50 a pair of hollow endwise abutting rod sections, of an internal splicing member snugly fitting the meeting ends of said sections, said rod sections and splicing member having co-operating devices for locating the joint between said rod sections at the longitudinal center of said splicing member, and other co-operating devices for yieldably locking said splicing member in said rod sections. 55

5. In a curtain rod, the combination with 60 a pair of hollow flat endwise abutting rod sections formed with notches in the meeting ends of their front faces and with holes in their front faces rearwardly of said notches, of a hollow internal splicing member snugly 65 fitting the meeting ends of said sections and formed with a central outwardly pressed protuberance on its front face adapted to engage with said notches and with other outwardly pressed protuberances adapted 70 to engage with said holes.

JAMES H. BOYE.
